WITNESSES

ATTORNEY

UNITED STATES PATENT OFFICE.

FRED AMERICUS BISHOP, OF PETERSBURG, VIRGINIA.

ANTIGLARE HEADLIGHT.

Application filed August 15, 1923. Serial No. 657,583.

To all whom it may concern:

Be it known that I, FRED A. BISHOP, a citizen of the United States, residing at Petersburg, in the county of Dinwiddie and

5 State of Virginia, have invented new and useful Improvements in Antiglare Headlights, of which the following is a specification.

This invention relates to improvements 10 in anti-glare devices for vehicle headlights and has for an object the provision of a device whereby the rays of light will be directed forwardly to a common point, so as to enable the driver of a vehicle to which 15 the invention is applied to plainly see the roadway and at the same time eliminate glare.

To this end the invention provides a unitary structure which may be secured within 20 a lamp in the path of the rays of light and adjusted to direct said rays forwardly in a manner to prevent them from interfering with the vision of persons approaching from an opposite direction.

25 With the above and other objects in view, the invention further includes the following novel features and details of construction, to be hereinafter more fully described, illustrated in the accompanying drawings 30 and pointed out in the appended claims.

In the drawings:

Figure 1 is a front elevation of an automobile head lamp with the invention applied thereto.

35 Figure 2 is a vertical central sectional view of the same.

Referring in detail to the drawings wherein like characters of reference denote corresponding parts, the invention is shown 40 applied to a head lamp having a casing 10 of the drum type, a reflector 11 and a lens 12 which is shown as secured in place by a ring 13. The electric bulb is shown at 14.

The anti-glare device which constitutes 45 the invention is located within the lamp casing and is in the form of a unitary structure which includes a frame 15. This frame

is of circular formation and is threaded exteriorly for adjustable engagement with threads 16 provided upon the inside of the 50 lamp casing.

Arranged concentrically within the frame 15 is a plurality of annular deflecting members 17. These members are secured within the frame 15 by means of strips 18 which 55 are arranged in the form of radial partitions, as shown in Figure 1 of the drawings. The members 17 converge forwardly and outwardly and are so arranged relatively as to direct the rays of light to a common 60 point in advance of the lamp.

By threading the frame 15 within the lamp casing, the device may be adjusted relative to the lamp 14, in accordance with the focus of the latter and when properly 65 positioned, the device may be held against accidental displacement by means of a set screw 19.

The invention is susceptible of various 70 changes in its form, proportions and minor details of construction and the right is herein reserved to make such changes as properly fall within the scope of the appended claim.

Having described the invention what is 75 claimed is:

An anti-glare headlight of the character described, comprising an externally threaded circular frame, the casing of a lamp threadedly engaging the frame therein, a plurality 80 of concentrically arranged outwardly converging members arranged within the frame, said members being secured within the frame by strips arranged in the form of radial partitions and focusing the members 85 toward a common center, the central member focusing forwardly and being independent of the other members and forming the hub from which the strips radiate, and means for adjustably holding the circular 90 frame to the casing.

In testimony whereof I affix my signature.

FRED AMERICUS BISHOP.
